UNITED STATES PATENT OFFICE.

CLARENCE C. THOMAS, OF PROVIDENCE, RHODE ISLAND.

DESIGN FOR A GRAVE MARK.

60,836.

Specification for Design.

Patented Apr. 11, 1922.

Application filed July 8, 1921. Serial No. 483,363. Term of patent 7 years.

To all whom it may concern:

Be it known that I, CLARENCE C. THOMAS, a citizen of the United States, residing at Providence, in the county of Providence and State of Rhode Island, have invented a new, original, and ornamental Design for Grave Marks, of which the following is a specification, reference being had to the accompanying drawings, forming part thereof.

The figure is a view of a grave mark of my new design.

I claim:

The ornamental design for a grave mark, as shown.

CLARENCE C. THOMAS.
